UNITED STATES PATENT OFFICE.

EDWARD C. BERGER, OF SOUTH BEND, INDIANA.

DESIGN FOR A SPATULA.

SPECIFICATION forming part of Design No. 32,481, dated April 10, 1900.

Application filed February 27, 1900. Serial No. 6,768. Term of patent 7 years.

To all whom it may concern:

Be it known that I, EDWARD C. BERGER, a citizen of the United States, residing at South Bend, in the county of St. Joseph and State 5 of Indiana, have invented and produced a new and original Design for a Spatula; and I do hereby declare the following to be a full, clear, and exact description of the same, reference being had to the accompanying drawings, 10 forming a part thereof.

My invention relates to a design for spatulas; and the essential feature of my design consists in a flat blade-like portion provided with sharp edges upon one of its sides and its 15 outer end and a curved handle, which is attached to the blade-like portion or spatula at one end, as will be more fully described hereinafter.

In the accompanying drawings, which represent my invention, Figure 1 is a plan view

of a spatula which embodies my design. Fig. 2 is an edge view of the same.

A represents the spatula, which is an elongated flat blade having a sharp edge B upon one of its sides and upon its outer end. The 25 two outer corners of the blade are made square; but both of its inner corners are slightly rounded, as shown. To the inner end of the spatula or blade-like portion A is secured a curved handle C.

Having thus described my invention, I 30 claim—

The design for a spatula, substantially as shown and described.

In testimony whereof I affix my signature 35 in presence of two witnesses.

EDWARD C. BERGER.
